INTERNAL COMBUSTION ENGINE

Edward L. Weitzel, Duluth, Minn.

Application July 6, 1934, Serial No. 734,058

7 Claims. (Cl. 123—61)

This invention relates to internal combustion engines of the Diesel type.

- An object of the invention is the provision of an internal combustion engine of the Diesel type in which a piston is movable in a cylinder and provided with a chamber connected with a source of compressed air with the opposite ends of the piston being provided with spring-controlled valves for supplying the opposite ends of the cylinder with compressed air directly from the chamber, the valves being controlled by differential pressures between the chambers in the piston and the combustion chambers at opposite sides of the piston.
- Another object of the invention is the provision of an internal combustion engine of the Diesel type in which two impulses are imparted to a revolving member at each revolution, the engine being so constructed that not only a high speed will be had but a greater horse power will be obtained for the weight of the engine.

A further object of the invention is the provision of an internal combustion engine of the Diesel type in which a combustion chamber is provided at each end of the cylinder and between the piston, the compressed air being introduced to the combustion chamber through a central chamber provided in the piston which is connected with a source of air under pressure, the supply of compressed air to the combustion chamber being controlled by the differential pressures existing between the chamber in the piston and the combustion chambers, springs being employed for closing the intake valves when the pressures on opposite sides of the valve have been equalized.

A still further object of the invention is the provision of an internal combustion engine of the Diesel type in which two power impulses are imparted during a single rotation of the flywheel, the flywheel being operated by a rod connected with the piston having a cam roller movable in a groove on the flywheel or master wheel for causing rotation of said wheel.

Another object of the invention is the provision of an internal combustion engine of the Diesel type in which a piston is slidably mounted in a cylinder with a combustion chamber at each end of the cylinder, the piston being provided with a water chamber and a compressed air chamber, a hollow piston rod being connected to the piston and in communication with the water chamber so that the piston is not only cooled internally but the rod is likewise cooled.

This invention will be best understood from a

consideration of the following detailed description, in view of the accompanying drawings forming a part of the specification; nevertheless, it is to be understood that the invention is not confined to the disclosure, being susceptible of such changes and modifications as define no material departure from the salient features of the invention as expressed in the appended claims.

In the drawings:

Figure 1 is a longitudinal section through one of the cylinders taken along the line 1—1 of Figure 2,

Figure 2 is an end view of the engine showing the co-ordinated relationship of a plurality of cylinders,

Figure 3 is a transverse vertical section taken along the line 3—3 of Figure 1,

Figure 4 is a side view of the complete engine,

Figure 5 is an enlarged vertical section of a pump for forcing liquid fuel into the combustion chambers of the cylinders, and

Figure 6 is an enlarged fragmentary view of part of the operating means for the pump piston for forcing the fuel into the combustion chamber.

Referring more particularly to the drawings, 10 designates a plurality of engine units which are arranged around a driving shaft 11 mounted in bearings 12 connected in any approved manner with the brackets 13 which are connected to water jackets 14 in any approved manner. It will be noted from Fig. 1 that the brackets 13 also provide bearings for cam shaft 15.

Each unit consists of a cylinder 20 embraced by the water jacket 14 and has heads 21 and 22 at the opposite ends thereof. These heads are hollow and are in communication with the water jacket 14. This water jacket is supplied with water by a pipe 23 in a manner which will presently be explained. A pipe 24 forms an outlet for the water from the jacket and this water is conducted back to the source.

A piston, designated by the numeral 25, is provided with a central chamber 26 for compressed air and two end chambers 27 and 28. A hollow piston rod 29 is connected to the piston 25 and is in communication with the chamber 27 which is in direct communication with the chamber 28 through a plurality of passages 30.

A sleeve 31 is connected with a source of water by means of a pipe 32 and this sleeve embraces 50 a tubular member 33 located centrally and longitudinally of the sleeve 31 so that the space between the tubular member 33 and the sleeve 31 forms a water conduit 34 which at its inner end is threaded into a boss 35 on one end of the piston 55

25 and this conduit is in direct communication with the chamber 28 so that water is supplied directly from the pipe 32 to the chambers 27 and 28 at the opposite ends of the piston 25.

5 The outer end of the sleeve 31 is closed by a cap 36 which is threaded onto the sleeve so that the cap may be removed when desired.

A check valve 37 is located in a valve cage 38 connected with the pipe 32 and is maintained 10 on its seat by a spring 39 to prevent the back flow of water from the sleeve 31 to the source of supply.

The rod 29 is hollow and is in open communication at 40 with the chamber 27 at the inner 15 end of said rod. The outer end of the rod is provided with a nipple 41 which is connected with the pipe 23 so that the water from the cylinder head and the rod 29 will be returned to the water jacket 14 and the hollow heads 21 and 22 of the 20 cylinder. This water, as has been previously explained, is discharged through the outlet pipe 24. The pipe 23 may be flexible or there may be provided a sliding connection for maintaining the hollow rod 29 in communication with the water 25 jacket 14.

The opposite ends of the piston 25 are provided with passages 45 and 46 which connect the opposite ends of the cylinders or combustion chambers 47 and 48, respectively, with the compressed 30 air chamber 26 in the piston. It will be noted that these passages are surrounded by the water jackets in the piston 25. An inlet valve 49 is located in each passage 45 and has a stem 50 projecting into the passage and engaged by a spring 35 51 for moving the valves 49 on their seats when the pressures in the chamber 26 and the combustion chamber 47 have been equalized.

Valves 52 are adapted to control the passages 46 and are maintained on their seats by means 40 of springs 53. These valves are closed when the pressure in the chamber 26 is equal to the pressure in the combustion chamber 48 and are maintained closed as long as these pressures are in equilibrium or the pressure is greater in the combustion chamber 48 than in the compressed air 45 chamber 26.

A pipe 55 is connected with a source of compressed air and is directly in communication with the tubular member 33. The inner end of the 50 tubular member is threaded, as shown at 56, into a wall 57 of the compressed air chamber 26. The inner end of the tubular member is provided with a nozzle 58 and this nozzle carries a check 55 valve 59 maintained on its seat by means of a spring 60 and this check valve prevents back flow of air from the chamber 26 to the supply pipe 55. It will be noted that either a flexible hose 60 may connect the tubular member 33 with the source of compressed air or a sliding sleeve may be employed which is connected between the source of supply and the tubular member 33 for supplying the tubular member with compressed air.

The head 21 is provided with exhaust passages 65 61 controlled by valves 62 adapted to engage seats 63. Each valve is operated by a stem 64 and is adapted to be closed by a spring 65.

Exhaust valves 66 are located in the head 22 and are also moved to closed position by means 70 of a spring 65 located within a housing 66. These valves are also provided with stems 64 which project beyond the housing 66 and are provided with a head 67 as are the stems 64 of the valves 62. Each of the housings 66 is provided with discharge 75 openings 68 for the exhaust gases.

A lever 70 is pivotally mounted at 71 on a bracket 72 on similarly positioned housings 66 at the opposite ends of the cylinder 20.

At each end of the cylinder 20 is a lever 73 pivotally mounted at one end on a bracket 72 5 and this lever is provided with a fork 74 embracing the fork 75 on the lever 70. The inner ends of the fork 74 are provided with slots 76 to receive pins 77 carried by the fork 75. The forks adjacent the cylinder head 21 embrace the outer end of the rod 29 while the similarly constructed forks adjacent the head 22 embrace the sleeve 31.

The outer end of the lever 70 adjacent the head 21 is provided with a cam roller 80 adapted to 15 engage a cam member 81 which is secured to the cam shaft 15. This cam member is provided with a raised portion 82 adapted when engaging the roller 80 for reciprocating the levers 70 and 73 adjacent the cylinder head 21 for opening the 20 exhaust valves 62.

The lever 70 adjacent the head 22 is provided with a cam roller 83 adapted to engage a cam member 84 having a raised portion 85 for moving the outer end of the lever 70 outwardly so 25 that the inner portion of the lever 70 will force the head 67 and the stem 64 inwardly and likewise the valve 66 to permit discharge of exhaust gases from the combustion chamber 48. The lever 73 adjacent the cylinder head 22 is operated 30 simultaneously with the lever 70 for opening the other exhaust valves 66.

The cam shaft 15 is provided with a gear 86 meshing with a gear 87 secured to the drive shaft 11. 35

A fuel oil pump 90 has a nozzle 91 opening into the combustion chamber 47 while a fuel pump 92 has a nozzle 93 opening into the combustion chamber 48.

Referring more particularly to Figs. 1, 5, and 6 40 it will be seen that a special construction of pump is provided having a cylinder 94 which has a pump barrel 95 adapted to be supplied by fuel oil by means of a pipe 96 opening into the barrel 95. A plunger 97 is slidably mounted in the barrel 95 45 and extends into the cylinder 94. A valve stem 98 passes through the outer end 99 of the cylinder 94 through the piston 97 and is provided with a valve 100 which projects into the respective combustion chamber when in open position. This 50 valve is adapted to engage its seat 101 formed in the end wall of the barrel 95.

An operating mechanism for the piston or plunger 97 and the valve stem 98 consists of a bracket 102 secured to or formed integrally with 55 the water jacket 14. On the upper free end of this bracket is pivotally mounted at 103 a bell-crank lever 104 having an arm 105 extending outwardly from the water jacket 14 and provided with a cam-engaging member 106 adapted to be 60 engaged by a cam 107 for rocking the arm 105 and likewise an arm 108 for a purpose which will be presently explained. The cam member is in the form of a disc 109 which is secured to the drive shaft 11. 65

The outer free end of the arm 108 is provided with a fork 110 which embraces a reduced portion 111 of the piston or plunger 97. Diametrically disposed pins 112 carried by the reduced portion 111 are received within the slots 113 formed in 70 the fork 110. A coil spring 115 tends to move the plunger or piston 97 to a normal outward position.

A lever 120 has a short arm pivoted at 121 on the arm 108 adjacent the pivot point 103 of the 75

bell-crank 104. The long arm or lever 120 is connected at 122 with a depending bar 123 which is formed of spring steel. The outer end of the lever 120 is provided with a fork 124 having slots 125 to receive pins 126 carried by the valve stem 98. A spring 130 engaging the cover 99 of the cylinder 94 tends to move the valve stem outwardly and seat the valve 100.

A lug 131 which is formed integrally with the depending member 123 is adapted to engage beneath the arm 108 so that when said arm is lowered the lever 120 will likewise be lowered. A cam member 132 is carried by the water jacket 14 and is adapted to be engaged by a toe 133 having an inclined face 134 for moving the depending member 123 outwardly from the arm 108 so that the lever will be released from the arm 108 whereby the spring 130 will seat the valve 100.

20 A flywheel or master wheel 140 is shown in Figs. 1, 2, and 4 and the outer surface of this wheel is provided with a cam groove having curved sections 141 and 142, 143 and 144. These grooves form a continuous groove around the rim of the flywheel 140.

25 Each of the outer ends of the rods 29 is provided with a cam roller 145 mounted upon an axle 146 carried by a reduced portion 147 of the rod 29. The rollers 145 are disposed within the cam grooves in the rim of the flywheel 140 so that as the rods 29 are reciprocated these rollers moving within the grooves will bear against one edge of the grooves and cause the flywheel to be revolved.

30 It will be noted that the hollow rod 29 moves through a bearing 150 which has a packing 151 embracing the rod. A bearing 152 receives the sleeve 31 and a packing 153 embraces the sleeve and prevents loss of fluid at this point.

35 It will be noted that I have shown three cylinders arranged around the drive shaft 11 so that there will be three piston rods having rollers 145 engaging the respective grooves in the rim of the flywheel 140 at 120° apart. The specific construction of the cylinder together with the piston and the related operating parts disclose an example of the construction of each of the internal combustion units.

40 The timing of each piston and the valves is such that two power impulses are imparted to the flywheel 140 at each revolution thereof.

45 Compressed air is supplied through the pipe 55 and the tubular member 33 to the central chamber 26 of each piston. As shown in Fig. 1 the combustion chamber is being scavenged by the compressed air from the chamber 26 with the exhaust valves 62 open. The piston 25, however, is at the end of the compression stroke for the chamber 48 and the liquid fuel valve 100 is shown open. In view of the fact that the cam 107 has sharply inclined walls the operation of the pump and the opening of the valve 100 is only momentary for supplying a small quantity of liquid fuel to the compressed air in the combustion chamber 48. As this liquid fuel begins to burn the compressed air is greatly heated and expanded so that the piston is moved towards the cylinder head 21.

50 The cams 85 adjacent the cylinder head 22 are out of engagement with the rollers 83 so that the exhaust valve 66 will remain closed.

55 The cams 82 are so shaped that they will maintain the exhaust valve 62 open until the combustion chamber 47 is thoroughly scavenged when the flap or disc portion of the member 81 will

receive the cam roller 80 and permit the spring 65 to close the exhaust valve.

Near the end of the compression stroke in the chamber 47 the cam 107^a on the drive shaft 11 will engage the member 106^a on arm 105^a and thereby operate the pump 90 for forcing the liquid fuel into the compressed air. The high temperature of the compressed air will cause burning of the liquid fuel and thereby increase the temperature of the compressed air so that when the piston 25 is on its return movement work will be exerted on said piston and the piston will be moved in the opposite direction.

60 These operations just described occur in each of the three cylinders and in a uniform manner with two power impulses imparted to the respective piston rods 29 during each revolution of the flywheel or master wheel 140.

65 Each valve 49 is mounted in a sleeve 49^a which is threaded into the wall of the passage 45. Each valve 52 is carried by a sleeve 52^a which is threaded to the wall of the passage 46 so that the valves 49 and 52 together with their springs are removable as a unit from the piston.

I claim:

70 1. In an internal combustion engine of the Diesel type, a cylinder, a piston dividing the cylinder into a pair of combustion chambers, one at each side of the piston, the piston having a chamber, passages connecting the chamber with the combustion chambers, inlet valves for controlling the passages, springs co-operating with the differential pressures between the piston chamber and the combustion chambers for causing closing of the valves, said differential pressures causing 75 opening of said valves, a tube having one end opening into the chamber in the piston, the other end projecting beyond the adjacent end of the cylinder and connected with a source of compressed air.

75 2. In an internal combustion engine of the Diesel type, a cylinder, a piston dividing the cylinder into a pair of combustion chambers, one at each side of the piston, the piston having a chamber, passages connecting the chamber with the combustion chambers, inlet valves for controlling the passages, springs co-operating with the differential pressures between the piston chamber and the combustion chambers for causing closing of the valves, said differential pressures causing 80 opening of said valves, a tube having one end opening into an end of the piston and connected with a source of compressed air, and a check valve in the tube for preventing back pressure from the piston to the tube.

85 3. In an internal combustion engine of the Diesel type, a cylinder, a piston in the cylinder having a central chamber for compressed air and a chamber embracing the central chamber and forming a water jacket, a tube in communication with the central chamber and with a source of compressed air, said tube projecting beyond one end of the cylinder, a sleeve enclosing the tube having the inner end in communication with the water jacket and the other end in communication with a source of water.

90 4. In an internal combustion engine of the Diesel type, a cylinder, a piston in the cylinder having a central chamber for compressed air and a chamber embracing the central chamber and forming a water jacket, a tube in communication with the central chamber and with a source of compressed air, said tube projecting beyond one end of the cylinder, a sleeve enclosing the tube having the inner end in communication with 95

- the water jacket and the other end in communication with a source of water, a water jacket embracing the cylinder, a hollow rod connected to the piston and in communication with the water jacket of the piston, the outer end of the rod projecting beyond the other end of the cylinder, and means for placing the outer end of the hollow rod in communication with the cylinder water jacket.
- 5 10. In an internal combustion engine, a cylinder, a piston in the cylinder and having an outer shell and an inner shell spaced from the walls of the outer shell so that the walls of the inner shell will not be affected directly by the intense heat 15 of combustion, said inner shell having a compressed air chamber, the opposite walls of the inner and outer shell being provided with aligned openings, sleeves connecting pairs of the aligned openings to provide communication between the 20 interior of the chamber in the inner shell and the cylinder, a valve closing the outer end of each sleeve, a spring for maintaining the valve closed, and means for supplying the chamber in the inner shell with air under pressure.
- 25 11. In an internal combustion engine, a cylinder, a piston in the cylinder and dividing the cylinder into a pair of combustion chambers at each side of the piston, said piston including an outer shell and an inner shell spaced from the walls of the outer shell, the inner shell having a compressed air chamber, sleeves forming passages 30 between the chamber in the inner shell and the

combustion chamber, a spring-controlled valve in each sleeve and adapted to be opened by pressure within the chamber in the inner shell, said sleeves providing means for aiding in supporting the inner shell within the outer shell and in spaced relation from the walls of the outer shell, a tube in communication with the inner chamber and connected to the piston, and means for supplying said tube with air under pressure.

5

7. In an internal combustion engine, a cylinder, 10 a piston in the cylinder and dividing the cylinder into a pair of combustion chambers at each side of the piston, said piston including an outer shell and an inner shell spaced from the walls of the outer shell, the inner shell having a compressed air chamber, sleeves forming passages 15 between the chamber in the inner shell and the combustion chamber, a spring-controlled valve in each sleeve and adapted to be opened by pressure within the chamber in the inner shell, 20 said sleeves providing means for aiding in supporting the inner shell within the outer shell and in spaced relation from the walls of the outer shell, a tube in communication with the inner chamber and connected to the piston, 25 means for supplying said tube with air under pressure, a valve cage at the inner end of the tube and projecting into the chamber, a valve in the cage to permit air under pressure to enter the chamber but to prevent the air in the chamber from entering the tube.

EDWARD L. WEITZEL.
